CLAIM

The ornamental design for a remotely controlled animal training receiver, as shown and described.

DESCRIPTION

FIG. 1 is a perspective view of a remotely controlled animal training receiver illustrating our new design;

FIG. 2 is a top view thereof;

FIG. 3 is a left side view thereof;

FIG. 4 is a bottom view thereof;

FIG. 5 is a right side view thereof; and,

FIG. 6 is an end view thereof.
